CATION-ACTIVE SURFACE ACTIVE QUATERNARY AMMONIUM COMPOUNDS
 Kermite Longley, Park Forest, Ill., assignor to Witco Chemical Company, Inc., New York, N.Y., a corporation of Delaware
 No Drawing. Filed Apr. 29, 1963, Ser. No. 276,203
 9 Claims. (Cl. 260—567.6)

My invention relates to the production of novel cation-active surface active chemical compounds which are useful for bactericidal, germicidal, antiseptic, algaeccidal, fungicidal, textile softening, corrosion inhibition, antistatic, emulsifying, foam modifying, ore beneficiation, and various other purposes for which certain heretofore known cationic surface active agents have been employed or suggested for use.

The specific cation-active surface active agents of my present invention are of the quaternary ammonium type and they are characterized by particularly advantageous properties, simplicity of production and markedly low cost. Certain of them, for instance, derived from lower dialkyl monoalkanolamines, can be represented by the formula

where R and R₁ are the same or dissimilar alkyl radicals each containing from 1 to 3 carbon atoms

where R₃ is an alkyl radical containing from 1 to 4 carbon atoms, n is a number up to and including 60, the total number of carbon atoms in R₂ being at least 18, v is a number at least 1 with the proviso that the weight ratio of (C₂H₄—O—)_v to R₂ is not greater than 1 to 4, X is a member selected from the group consisting of (1) alkyl and alkenyl radicals containing from 1 to 4 carbon atoms, (2) lower aliphatic-monocyclic aryl hydrocarbon radicals, (3) sulfo-aromatic hydrocarbon radicals, (4) chloro-aromatic hydrocarbon radicals; and A is an anion.

Again, various of the quaternary ammonium compounds of my invention which are derived from lower monoalkyl dialkanolamines can be represented by the formula

where R, R₂, X, A and v have the same meanings as referred to under Formula I.

Still others of the quaternary ammonium compounds of my invention can be represented by the formulae

where R, R₁, X and A have the same meanings as referred to under Formula I, and R₄—O—R₅ is a polyoxyethylene-polyoxypropylene radical containing at least 6 oxypropylene groups and where the weight ratio of the polyoxyethylene radical to the polyoxypropylene radical is not greater than 1 to 4, the total number of oxypropylene groups not exceeding 60.

2

Still others of the quaternary ammonium compounds of my invention can be represented by the formula

(V)

where R, R₂, X, A and v have the meanings set forth above, and R₆ has the same meaning as R₂, the sum of the n's not exceeding 60 and the total number of carbon atoms in the sum of R₂ and R₆ being at least 18.

Various others of the quaternary ammonium compounds of the present invention can be represented by the formula

(VI)

where R₂ is

and R₃ is an alkyl radical containing from 1 to 4 carbon atoms, and n totals a number not exceeding 60 with the proviso that the number of carbon atoms in the total of the R₂ radicals is at least 18, v is a number at least 1 with the proviso that the weight ratio of (C₂H₄—O—)_v to R₂ is not greater than 1 to 4, X is a member selected from the group consisting of (1) alkyl and alkenyl radicals containing from 1 to 4 carbon atoms, (2) lower aliphatic-monocyclic aryl hydrocarbon radicals, (3) sulfo-aromatic hydrocarbon radicals, (4) chloro-aromatic hydrocarbon radicals; and A is an anion.

In those cases where R₂, for instance, is derived from propyleneoxide, there will be at least 6, and there may be up to 60 or more, of such propyleneoxide groups in R₂, but, particularly, it is desired that R₂ contain from 8 to 25 or 30 oxypropylene groups. Where R₂, for instance, is derived from α -epoxides containing more than 3 carbon atoms, a lesser number of such oxyalkylene groups can be present, subject to the limitation that R₂, if it is the only polyoxyalkylene radical present in which the oxyalkylene group contains 3 or more carbon atoms, contains at least 18 carbon atoms. The R and R₁ alkyl radicals may be the same or dissimilar and each contains from 1 to 3 carbon atoms. X is a lower alkyl or alkenyl radical containing from 1 to 4 carbon atoms, or is an aliphatic-aryl radical containing from 7 to 9 carbon atoms, notably an alkaryl radical; and A is an anion such as chlorine or bromine. The term " α -epoxide," as used herein, is intended to cover those compounds, of the type here involved, where there are two vicinal carbon atoms connected to one oxygen atom independently of the position of such group in the molecule.

The terms "polyoxyalkylene," "polyoxypropylene" and "polyoxyethylene," to the extent that they are used herein or in the claims, are employed in their usual or conventional manner. Thus, in the case of the polyoxyalkylene radical derived from α -epoxides containing from 3 to 6 carbon atoms, to wit, R₂ in the above formulae, the same may be represented by

where R₃ is an alkyl radical containing from 1 to 4 carbon atoms, and, as indicated above, since R₂, for instance, may contain a minimum of 18 carbon atoms, n is at least 6 in the case of the polyoxyalkylene radical being polyoxypropylene and n is at least 3 in the case of the polyoxyalkylene radical being polyoxyhexylene. Where the

polyoxyalkylene radical is polyoxypropylene, it may be represented by the formula

n being from 6 to 60.

The foregoing illustrate the polyoxyalkylene and polyoxypropylene radicals where the vicinal carbons are terminal. In the broader, but less preferred, embodiments of my invention, however, the vicinal carbons need not be terminal. A typical illustration of the latter is a polyoxyalkylene radical derived from 2,3-butylene oxide.

Most of the quaternary ammonium compounds of the present invention fall into the category of or correspond to reaction products of quaternizing esters having a hydrocarbon alkyl or alkenyl radical containing from 1 to 4 carbon atoms or a benzyl radical or a dimethylbenzyl radical or a lower alkyl substituted or chloro or nitro substituted benzyl radical, and an anion, with adducts of (a) aliphatic mono-lower alkyl hydroxyalkyl amines or di-lower alkyl hydroxyalkyl amines in which no single alkyl radical contains more than 3 carbon atoms, with (b) an α -epoxide containing at least 3 and advantageously from 3 to 8 carbon atoms, the molal ratio of (a) to (b) being 1 of (a) to at least 6 of (b) when said α -epoxide contains 3 carbon atoms and ranging down to at least 2.5 of (b) when said α -epoxide contains 8 carbon atoms.

While, as indicated, many of the novel and useful cation-active surface active agents of my invention can be represented by the above formulae, in certain cases they may be described in the form of reaction products of identified ingredients, as hereafter pointed out, since the active constituent or constituents thereof need not be separated out and recovered as such, the reaction products being usable as such for many purposes without the necessity for resorting to concentration, purification or recovery steps. Thus, for example, although this will be pointed out and described in more detail hereafter, quaternary ammonium compounds which are particularly useful and which may simply and inexpensively be produced are reaction products of aromatic quaternizing esters in the form of alkyl and alkenyl halides, sulfates and sulfonates containing from 1 to 4 carbon atoms, exemplified by methyl chloride, allyl chloride, methyl chloracetate, and 1 and 2 carbon atom alkyl sulfates; or quaternizing esters in the form of halides, sulfates and sulfonates advantageously containing from 7 to 9 carbon atoms exemplified by benzyl chloride, dimethylbenzyl chloride, and phenyl ethyl chloride, with adducts of (a) hydroxy alkyl amines in which any alkyl radical contains from 1 to 3 carbon atoms, such as ethyl diethanolamine or diethyl ethanolamine, with (b) propyleneoxide or butyleneoxides, said adducts containing 1 mol of (a) to from 6, and preferably from 8, to 30 mols of (b). Purification steps can, if desired, be employed as, for instance, separating unreacted tertiary amines by distillation, etc.

It is important to note that it is critical to my present invention that there be present in the molecule oxyalkylene groups derived from an α -epoxide containing at least 3 carbon atoms. Ethylene oxide, for instance, as such, is not operative in the practice of my invention since it produces compounds whose properties are radically different from those obtained in accordance with my invention and which would be useless for many of the purposes for which the cation-active surface active agents of my invention are adapted and intended. The most important embodiment of the α -epoxides whose use is contemplated by my invention in the production of the cation-active surface active agents is propyleneoxide

The α -epoxides containing 4, 5, 6 or more carbon atoms can be used, but, for general reasons of lack of economy or commercial availability, are not preferred. Typical of

such latter α -epoxides are butylene oxides such as 1,2-butylene oxide, pentylene epoxides, hexylene epoxides, heptylene epoxides, octylene epoxides, dodecylene epoxides, and C_{16} - C_{18} olefin oxides or epoxides, and, as well, 5 styrene epoxides. It will be seen that most of those of the α -epoxides in which the vicinal carbons are terminal can conveniently be represented by the formula

where R is an alkyl radical. In the case of propylene oxide, R_2 is CH_3 , and in the representation of the group of propylene oxide, butylene oxides, pentylene oxide and hexylene oxide R_2 contains from 1 to 4 carbon atoms. In the higher molecular weight alkylene oxides, R_2 may contain as high as 16 carbon atoms.

While, as I have stated above, the use of ethyleneoxide as the sole alkylene oxide is inoperative for my purposes, small proportions thereof, not to exceed 25% and better still not to exceed 20% by weight of the propyleneoxide or other α -epoxides employed, can be utilized as hereafter described. Mixtures of two or more of the α -epoxides containing at least 3 carbons can, of course, be used as such, as well as in conjunction with ethyleneoxide, subject to the limitation that the ethyleneoxide must not exceed the aforesaid 20% to 25% of the weight of said α -epoxides.

The cation-active surface active agents of my invention are advantageously prepared by initially condensing, for instance, a monoalkyl or monoalkenyl di-hydroxyalkyl amine in which each alkyl radical or alkenyl radical contains from 1 to 3 carbon atoms, for example, monoethyl diethanolamine or monomethyl diisopropanolamine; or a dialkyl or dialkenyl mono-hydroxyalkyl amine in which each alkyl radical or alkenyl radical contains from 1 to 3 carbon atoms, for example, diethyl monoethanolamine or dimethyl isopropanolamine; with propyleneoxide or other α -epoxide containing at least 3 carbon atoms, advantageously in the presence of a conventional oxyalkylating catalyst such as sodium hydroxide or potassium hydroxide, whereby to produce an intermediate or adduct containing at least 6 oxypropylene groups. The resulting adduct is then reacted with a quaternizing ester in the form of lower alkyl or alkenyl halides, lower alkyl esters of sulfuric acid, lower alkyl esters of sulfonic acids, lower alkyl and alkenyl haloacetates, or aromatic or lower aliphatic-aromatic quaternizing esters, to convert said adduct into the cation-active surface active agents of my present invention. Illustrative examples of such quaternizing esters are methyl chloride, methyl bromide, ethyl chloride, ethyl bromide, methyl iodide, allyl chloride, allyl bromide, methyl chloracetate, ethyl chloracetate, vinyl chloracetate, dimethyl sulfate, diethyl sulfate, benzyl chloride and dimethylbenzyl chloride, as well as their corresponding bromides; methylbenzyl chloride and bromide; phenylmethyl halides such as the chloride and bromide; phenylethyl chloride and bromide; substituted phenyl lower alkyl (from 1 to 4 carbon atoms) halides as, for example, o-chlorobenzyl chloride and ρ -nitrobenzyl chloride and bromide; and monocyclic arylsulfonic acid lower alkyl esters such as the methyl and ethyl esters of benzene sulfonic acid, ρ -toluene sulfonic acid, and o-toluene sulfonic acid.

Where the quaternizing esters are in the form of lower alkyl or alkenyl halides, lower alkyl esters, etc., as described above, the alkyl and alkenyl groups should contain not more than 4 carbon atoms and, better still, should contain only 1 or 2 carbon atoms. Where said quaternizing agents contain an aryl radical, it is particularly advantageous that such aryl radical be a benzene radical which is connected to a divalent hydrocarbon radical such as $-\text{CH}_2-$ or $-\text{CH}_2-\text{CH}_2-$ or to a lower alkyl radical, that is one containing not more than 4 carbon atoms, especially $-\text{CH}_3$ or $-\text{C}_2\text{H}_5$. The aromatic or lower aliphatic-aromatic quaternizing esters, for best results, should contain from 7 to 9 carbon atoms. The speed of qua-

ternization in any given instance will be governed by the reactants and the reaction conditions including the temperature and solvent medium utilized.

Illustrative examples of the intermediate condensation products or adducts which are subsequently converted into the cation-active surface active agents or quaternary ammonium compounds encompassed by my present invention are as follows:

- (a) Condensation products of 1 mol of dimethylethanolamine with 6 to 10 mols of propyleneoxide.
- (b) Condensation products of 1 mol of dimethylisopropanolamine with 15 mols of propyleneoxide.
- (c) Condensation products of 1 mol diethylethanolamine with 8 to 20 mols of propyleneoxide.
- (d) Condensation products of 1 mol of phenylethanolamine with 10 to 25 mols of propyleneoxide.

- (e) Condensation products of $\frac{1}{2}$ mol of diethylethanolamine and $\frac{1}{2}$ mol of monoethyldiethanolamine with 6 to 30 mols of propyleneoxide.
- (f) Condensation products of 1 mol of 2-amino-1,3-propanediol with 8 to 25 mols of propyleneoxide.

- (g) Condensation products of 1 mol of phenyldiethanolamine with 6 to 25 mols of propyleneoxide.

- (h) Condensation products of 1 mol of diethylethanolamine with 1 to 2 mols of ethyleneoxide, reacted with 20 mols of propyleneoxide.

- (i) Condensation products of 1 mol of diethylethanolamine with 30 to 40 mols of propyleneoxide.

- (j) Condensation products of 1 mol of diethylethanolamine with 10 to 20 mols of propyleneoxide and then with 1 mol of ethyleneoxide.

- (k) Condensation products of 1 mol of diallylethanolamine with 8 to 25 mols of propyleneoxide.

- (l) Condensation products of 1 mol of diethylethanolamine with 6 to 10 mols of butyleneoxide.

The amines which are utilized in the production of the intermediate adducts or condensation products with the propylene oxide or other α -epoxides are particularly advantageously of aliphatic or acyclic character. They contain at least one reactive hydrogen in an hydroxy group which is linked to the quaternary ammonium nitrogen through an alkylene group containing from 1 to 3 carbon atoms. Illustrative examples of such amines are alkyl hydroxy amines, e.g., monomethylethanolamine, monoethylmethanolamine, monomethylmethanolamine, dimethylethanolamine, diethylethanolamine, diallylethanolamine, hydroxyethyl ethylenediamine, and N,N-dimethyl-N'-diisopropanol propylenediamine-1,3. Such amines may contain nonreactive substituents such as nitro groups, ether and thioether groups, CN groups, and the like, but, in general, best results will be obtained with the unsubstituted amines. Compatible mixtures of any two or more of said amines, in various proportions, can, of course, be utilized in the production of the intermediate condensation products.

The radical A can be any negative or salt-forming radical as, for instance, halogen such as chlorine, bromine and iodine; hydroxy; sulfate; nitrate; phosphate; acetate; formate; sulfonic acids; and the like. Of particular importance are those of the cation-active surface active agents of my invention in which the anion is chlorine or bromine. Various of said anionic radicals can be introduced directly into the molecules; and, in the case of others, they can be made, for instance, by substitution for halogen in the cation-active surface active agents of my present invention by known techniques as, for instance, by metathesis procedures.

The following examples are illustrative of the production of typical cation-active surface active agents in accordance with my invention. It will be understood that other reactants can be utilized, proportions modified, temperature and other conditions, and concentration or purification procedures, employed, all within the guiding principles taught herein, without departing from the essential teachings disclosed herein.

Example 1

(a) 93 grams (1 mol) of dimethylethanolamine are placed in an autoclave from which the air is displaced by nitrogen. Then 74 grams (1 mol) of propylene oxide are pumped into the dimethylethanolamine in said autoclave and reacted while maintaining the temperature below 25 degrees C. The resulting reaction mixture is heated to about 150 degrees C. and 1406 (19 mols) of propylene oxide are added to the autoclave over a period of 6 hours while maintaining a nitrogen pressure in the autoclave, said reaction being advantageously carried out in the presence of 2 to 3 grams of potassium hydroxide as a catalyst. The rate of addition of the propylene oxide is controlled so that the pressure in the autoclave does not exceed 2 atmospheres and the temperature is controlled so as not to exceed about 150 degrees C. Upon completion of the reaction, the reaction mixture is cooled to below 100 degrees C. and flushed out with gaseous nitrogen.

(b) To 50 grams of the intermediate condensation product or adduct of part (a) hereof there are added 5 grams of butyl chloride in 10 grams of methanol and the resulting mixture is refluxed, with stirring, for 5 hours. A yield in excess of 90% of theoretical of the following product is obtained:

where R_2 is a polyoxypropylene radical containing approximately 20 oxypropylene groups.

Example 2

(a) 119 grams (1 mol) of monomethyldiethanolamine are reacted first with 74 grams (1 mol) and then with an additional 1036 grams (14 mols) of propylene oxide in the manner described in part (a) of Example 1.

(b) 100 grams of the adduct of part (a) of this Example 2 are reacted with 8 grams of ethyl chloride in 16 grams of methanol, in the manner described in part (b) of Example 1. The final reaction product, in a yield of the order of 90%, comprises the following product:

where R_2 are polyoxypropylene radicals the total of which contains approximately 15 oxypropylene groups.

Example 3

(a) 117 grams (1 mol) of diethylethanolamine are reacted with a total of 740 grams (10 mols) of propylene oxide in the manner described in part (a) of Example 1.

(b) 100 grams of the adduct of part (a) of this Example 3 are reacted with 7 grams of dimethylbenzyl chloride in 15 grams of methanol, in the manner described in part (b) of Example 1. The final reaction product, in a yield of the order of 90%, comprises the following product:

where R_2 is a polyoxypropylene radical containing approximately 10 oxypropylene groups.

Example 4

(a) 131 grams (1 mol) of diethylmonoisopropanolamine are reacted with a total of 888 grams (12 mols) of propylene oxide in the manner described in part (a) of Example 1.

(b) 50 grams of the adduct of part (a) of this Example 4 are reacted with 6 grams of benzyl chloride in

12 grams of methanol, in the manner described in part (b) of Example 1. The final reaction product, in a yield in excess of 80%, comprises the following product:

where R₂ is a polyoxypropylene radical containing approximately 12 oxypropylene groups. 10

Example 5

(a) 117 grams (1 mol) of diethylethanolamine are reacted with 44 grams (1 mol) of ethylene oxide and then with 700 grams (somewhat less than 10 mols) of propylene oxide, in the manner described in part (a) of Example 1.

(b) 50 grams of the adduct of part (a) of this Example 5 are reacted with 4 grams of ethyl bromide in 8 grams of methanol, in the manner described in part (b) of Example 1. The final reaction product, in a yield in excess of 80%, comprises the following product:

where R₂ is a polyoxypropylene radical containing approximately 10 oxypropylene groups.

This application is a continuation-in-part of my applications Serial Nos. 22,099 and 22,115, each filed April 14, 1960.

What I claim as new and desire to protect by Letters Patent of the United States is:

1. A quaternary ammonium compound corresponding to the formula

where R and R₁ are the same or dissimilar alkyl radicals each containing from 1 to 3 carbon atoms, R₂ is

where R₃ is an alkyl radical containing from 1 to 4 carbon atoms, n is a number up to and including 60, the total number of carbon atoms is R₂ being at least 18, v is a number at least 1 with the proviso that the weight ratio of (C₂H₄-O-)_v to R₂ is not greater than 1 to 4, X is a member selected from the group consisting of (1) alkyl and alkenyl radicals containing from 1 to 4 carbon atoms, and (2) benzene; lower alkyl benzenes in which the lower alkyl radicals contain from 1 to 4 carbon atoms,

and their methyl and ethyl nuclearly substituted derivatives; and the mono-halo, mono-nitro and mono-sulfonic nuclearly substituted derivatives of the foregoing; and A is an anion.

2. A quaternary ammonium compound corresponding to the formula

where R₂ is

and R₃ is an alkyl radical containing from 1 to 4 carbon atoms, n is a number up to and including 60, the total number of carbon atoms is R₂ being at least 18, X is a 75

member selected from the group consisting of (1) alkyl and alkenyl radicals containing from 1 to 4 carbon atoms, and (2) benzene; lower alkyl benzenes in which the lower alkyl radicals contain from 1 to 4 carbon atoms,

and their methyl and ethyl nuclearly substituted derivatives; and the mono-halo, mono-nitro and mono-sulfonic nuclearly substituted derivatives of the foregoing; and A is an anion.

3. A quaternary ammonium compound corresponding to the formula

where R is an alkyl radical containing from 1 to 3 carbon atoms, R₂ is

where R₃ is an alkyl radical containing from 1 to 4 carbon atoms, n is a number up to and including 60, the total number of carbon atoms in R₂ being at least 18, v is a number at least 1 with the proviso that the weight ratio of (C₂H₄-O-)_v to R₂ is not greater than 1 to 4, X is a member selected from the group consisting of (1) alkyl and alkenyl radicals containing from 1 to 4 carbon atoms, and benzene; lower alkyl benzenes in which the lower alkyl radicals contain from 1 to 4 carbon atoms,

and their methyl and ethyl nuclearly substituted derivatives; and the mono-halo, mono-nitro and mono-sulfonic nuclearly substituted derivatives of the foregoing; and A is an anion.

4. A quaternary ammonium compound corresponding to the formula

45 where R and R₁ are the same or dissimilar alkyl radicals each containing from 1 to 3 carbon atoms, R₄-O-R₅ is a polyoxyethylene-polyoxypropylene radical containing at least 6 oxypropylene groups and where the weight ratio of the polyoxyethylene radical to the polyoxypropylene radical is not greater than 1 to 4, the total number of oxypropylene groups not exceeding 60, X is a member selected from the group consisting of (1) alkyl and alkenyl radicals containing from 1 to 4 carbon atoms, and (2) benzene; lower alkyl benzenes in which the lower alkyl radicals contain from 1 to 4 carbon atoms,

60 and their methyl and ethyl nuclearly substituted derivatives; and the mono-halo, mono-nitro and mono-sulfonic nuclearly substituted derivatives of the foregoing; and A is an anion.

5. A quaternary ammonium compound corresponding to the formula

where R is an alkyl radical containing from 1 to 3 carbon atoms, R₄-O-R₅ is a polyoxyethylene-polyoxypropylene radical containing at least 6 oxypropylene groups and where the weight ratio of the polyoxyethylene radical to the polyoxypropylene radical is not greater than 1 to 4, the total number of oxypropylene groups not exceeding 60, X is a member selected from the group consisting of

(1) alkyl and alkenyl radicals containing from 1 to 4 carbon atoms, and benzene; lower alkyl benzenes in which the lower alkyl radicals contain from 1 to 4 carbon atoms,

and their methyl and ethyl nuclearly substituted derivatives; and the mono-halo, mono-nitro and mono-sulfonic nuclearly substituted derivatives of the foregoing; and A is an anion.

6. A quaternary ammonium compound corresponding to the formula

where R is an alkyl radical containing from 1 to 3 carbon atoms, R_2 is

R_6 is

where R_3 is an alkyl radical containing from 1 to 4 carbon atoms, n and n' are numbers the sum of which does not exceed 60, the total number of carbon atoms in the sum of R_2 and R_6 being at least 18, v is a number at least 1 with the proviso that the weight ratio of $(\text{C}_2\text{H}_4-\text{O}-)_v$ to the sum of R_2 and R_6 is not greater than 1 to 4, X is a member selected from the group consisting of (1) alkyl and alkenyl radicals containing from 1 to 4 carbon atoms, and (2) benzene; lower alkyl benzenes in which the lower alkyl radicals contain from 1 to 4 carbon atoms,

and their methyl and ethyl nuclearly substituted derivatives; and the mono-halo, mono-nitro and mono-sulfonic nuclearly substituted derivatives of the foregoing; and A is an anion.

7. A quaternary ammonium compound corresponding to the formula

where R is an alkyl radical containing from 1 to 3 carbon atoms, R_2 is

and n totals a number from 8 to 30, X is a member selected from the group consisting of (1) alkyl and alkenyl radicals containing from 1 to 4 carbon atoms, and (2) benzene; lower alkyl benzenes in which the lower alkyl radicals contain from 1 to 4 carbon atoms,

and their methyl and ethyl nuclearly substituted derivatives; and the mono-halo, mono-nitro and mono-sulfonic nuclearly substituted derivatives of the foregoing; and A is an anion.

5 8. A quaternary ammonium compound corresponding to the formula

10 where R is an alkyl radical containing from 1 to 3 carbon atoms, R_2 is

and n totals a number from 8 to 30, X is a member selected from the group consisting of (1) alkyl and alkenyl radicals containing from 1 to 4 carbon atoms, and (2) benzene; lower alkyl benzenes in which the lower alkyl radicals contain from 1 to 4 carbon atoms,

20 and their methyl and ethyl nuclearly substituted derivatives; and the mono-halo, mono-nitro and mono-sulfonic nuclearly substituted derivatives of the foregoing; and A is an anion.

25 9. A quaternary ammonium compound corresponding to the formula

30 where R_2 is

35 and R_3 is an alkyl radical containing from 1 to 4 carbon atoms, and n totals a number not exceeding 60 with the proviso that the number of carbon atoms in the total of the R_2 radicals is at least 18, v is a number at least 1 with the proviso that the weight ratio of $(\text{C}_2\text{H}_4-\text{O}-)_v$ to R_2 is not greater than 1 to 4, X is a member selected from the group consisting of (1) alkyl and alkenyl radicals containing from 1 to 4 carbon atoms, and (2) benzene; lower alkyl benzenes in which the lower alkyl radicals contain from 1 to 4 carbon atoms,

40 and their methyl and ethyl nuclearly substituted derivatives; and the mono-halo, mono-nitro and mono-sulfonic nuclearly substituted derivatives of the foregoing; and A is an anion.
